UNITED STATES PATENT OFFICE.

CHRISTIAN A. FREDERICKS, OF BROOKLYN, NEW YORK.

REFRIGERATOR-BUILDING.

SPECIFICATION forming part of Letters Patent No. 373,229, dated November 15, 1887.

Application filed July 29, 1887. Serial No. 245,609. (No model.)

To all whom it may concern:

Be it known that I, CHRISTIAN A. FREDERICKS, a citizen of the United States, and a resident of Brooklyn, Kings county, New York, 5 have invented certain new and useful Improvements in Refrigerator-Buildings, of which the following is a specification.

My invention relates to means for cooling rooms or chambers for cold-storage, such as 10 rooms for storing carcasses of beef, mutton, &c.

In carrying out my invention I construct a tight narrow cold-air reservoir or chamber, either within the storage-room or above it, as herein shown, and in this reservoir I place a 15 deep tight vessel for containing the refrigerant, which in this case comprises a mixture of ice and salt. This vessel is in the nature of a tube or pipe of sheet metal, which stands on end, and at its upper end projects through the 20 ceiling into the charging-room above the room where the cold-air reservoir is constructed. The refrigerant-vessel is covered at its charging end with a removable cap. An air-conduit conducts cold dry air from the bottom of 25 the reservoir to the storage-room, which it enters at or near the ceiling thereof, and a ventilating-conduit, which takes air from the ceiling or upper part of the storage-room, extends up into the room above and discharges 30 said air into the cold-air reservoir at or near its top. Thus I obtain a circulation of cold dry air downward through the cold-air reservoir, the air being admitted to and taken from the storage - room at the ceiling. Suitable 35 dampers or valves are employed for controlling the flow of air through the conduits. As the film of air in the lower part of the cold-air reservoir surrounding the refrigerant-vessel becomes extremely cold, and as the air taken 40 from the storage-room and admitted to the upper part of said reservoir is often humid and sometimes charged quite heavily with moisture from the carcasses in the storage-room, I find that this moisture will collect on the 45 walls of the refrigerant-vessel in the form of frost, and will accumulate thereon at times to such an extent as to substantially fill the narrow space between the wall of said vessel and the adjacent wall of the cold-air reservoir. In 50 any case the coating of frost forms a sort of heat-intercepting jacket on the refrigerant-vessel and impairs the efficiency of the latter

as a heat-absorber. To obviate this difficulty and to provide an efficient and simple means of preventing the accumulation of frost on the 55 refrigerant-vessel, as well as to remove the moisture from the air passing through the cold-air reservoir, is one of the most important objects of my invention. I effect this result by providing the refrigerant-vessel with a narrow 60 annular drip aperture or apertures near its upper end, through which the brine from the charging end or receiver of said vessel will ooze or drip and flow on and over the exterior surface of the refrigerant-vessel, so as to keep 65 said surface constantly wet with brine. This brine will prevent the formation of frost on the surface it covers, and it will also absorb the moisture from the air and carry it off into the drip pan or trough below. The brine of 70 course is furnished by the mixture of ice and salt placed in the hopper-like upper end or receiver of the refrigerant-vessel.

In order that my invention may be more fully understood, reference may be had to the 75 accompanying drawings, wherein—

Figure 1 is a vertical sectional elevation of a building provided with my refrigerating devices. Fig. 2 is a detached and enlarged view, partly in section, of one of the refrigerant-vessels; and Fig. 3 is a transverse section of said refrigerant-vessel on line 3 3 in Fig. 2. Figs. 4 and 5 illustrate slightly-modified constructions that will be hereinafter described.

In Fig. 1, which shows the preferred arrangement, A represents the storage-room or room to be kept cool; A', a room above the storage-room, containing the cold-air reservoir and refrigerant-vessels, and A² the charging-room above room A'. The rooms A A' should 85 have walls and ceilings constructed to prevent the passage of heat to the rooms from the outside.

a is the door leading to the storage-room, and a' a' are suitable windows to admit light 95 thereto.

B B are the cold-air reservoirs, in this case shown as arranged at the sides of the room A', and formed by partitioning off a narrow space therefrom with heat-intercepting partitions b b.

C C are the upright refrigerant-vessels arranged in the reservoirs B B. These vessels may stand side by side in the reservoir and be set at any desired distance apart. Their num-

ber will depend on the size of the storage-room and the reduction of temperature desired. I usually construct the vessel C open at the bottom, and set it on a block or beam, c, which 5 will leave space enough for the water to drip out below into a drip pan or trough, d, whence it will be led away in the usual manner. As sawdust from the ice and other débris will in time accumulate at the bottom of vessel C, 10 I usually provide said vessel with an opening in its side near the bottom. In the drawings a wicket or slide, e, arranged to play in vertical guides, is shown. This wicket closes such an opening; and in partition b may be 15 placed a tightly-closing door opposite wicket e, to provide access to the latter. Any means of cleaning may be used, however. This feature forms no essential part of my present invention. The vessel C has tight non-ap- 20 tured walls when in use—that is, the wicket e will be closed, normally—and the air which flows down around vessel C does not come in contact with the ice (G in Fig. 2) at any point. At its upper end, which projects up through 25 the ceiling of room A', the vessel C is provided with a somewhat-enlarged hopper-like receiver, c', provided with a cap or cover, c'. D is a conduit leading from the lower part of reservoir B to room A, which it enters at 30 the ceiling. There may be any desired number of these conduits, and they admit cold dry air to the storage-room. Each conduit has a valve or damper, g, to cut off and regulate the flow of air through the same.

35 E is a conduit leading from the ceiling of the storage-room up into the room above and entering the cold-air reservoir at or near its top. This conduit should enter the storage-room at a point as far as convenient from the 40 point where conduit D enters said room. Conduit E draws off the warmer moist air from room A and delivers it into the top of the cold-air reservoir. It is or may be provided with a regulating valve or damper, g', similar to that of the conduit D. There may be 45 any desired number of these conduits E.

Referring most particularly to Figs. 2 and 3, I will now describe the construction of the vessel C and the device or means whereby the 50 formation of frost thereon is prevented. Ordinarily, in constructing this vessel I make the receiver c' separate from the body of vessel C and construct its lower end to slip over and fit loosely about the end of said vessel, so as 55 to leave between them, where they overlap, a very narrow annular outlet or passage, h, Figs. 2 and 3, down which the brine may drip or ooze from the receiver. This downwardly-directed passage or outlet should be so narrow 60 or contracted as to prevent too copious an outflow of the brine, but of sufficient width to allow a continuous drip. A simple loosely-fitted telescope-joint will serve. The brine will always keep the passage filled and prevent the 65 entry of air thereat, and it will flow down and over the vessel by gravity. This drip-passage

70 h should be at the upper part of the vessel C, so as to keep all the surface of said vessel moistened with brine, and I find it convenient to form said passage at the junction of the receiver c' with the body of the vessel. However, the joint forming the said passage might be in the body of the vessel itself at a point a little below the receiver. There might also be more than one joint of this kind, with a 75 drip-passage h at each. This would be advisable where vessel C is very long.

In Fig. 4 I have shown the upper portion of a vessel C as having a joint in its body just below receiver c' and a drip-passage h thereat. 80

In Fig. 5, which is a cross-section at the joint, I have shown the outer and upper tubular member of the joint slightly crimped, so as to divide up the annular passage h into several passages arranged around the body of 85 the vessel C.

Fig. 5 is on a larger scale than the other figures.

Any similarly-constructed downwardly-directed narrow interstitial passage (or passages) 90 will serve, so long as the object sought is effected, which is to keep the exterior surface of the body of vessel C moistened with brine from the interior of the vessel above.

In Fig. 5 the passages h are made somewhat wide, and are shown as loosely filled with some fibrous or textile material, h', which takes up the brine like a wick and delivers it to the surface of the vessel below. 95

It should be understood that while my refrigerant-vessel C is open at the bottom, and has a wicket-closed aperture, e, for cleaning out near the bottom, and has the narrow outlet-passages h for the brine near the top, it is a tight vessel in the sense that the air flowing 100 down and around it does not come in contact with the ice in said vessel, and is therefore kept dry. If the walls of vessel C were made of wire-gauze, for example, or of perforated metal, my object would be defeated. Having 105 a vessel with tight non-apertured walls, I employ in connection therewith my device for preventing frost from forming on said walls. If frost should form during the period just preceding the renewal of the ice and salt, as it 115 may to some extent, the brine flowing down after the renewal will remove the same completely.

In my pending application, Serial No. 235,185, I have shown a refrigerating apparatus 120 with a tight cold-air reservoir and a tight refrigerating-vessel similar to vessel C arranged therein. I have also shown in said application conduits for air leading from the storage-room at its ceiling to said cold-air reservoir. I wish 125 to say that I do not herein claim these features, broadly, but only their special arrangement, as represented in Fig. 1, and the device for preventing the accumulation of frost on the refrigerant-vessel. This last-named device 130 may, however, be employed on refrigerant-vessels arranged in various ways, and it is not

limited to the peculiar arrangement of the refrigerant-vessel and cold-air chamber as seen in Fig. 1. For example, it is immaterial, so far as this frost-preventing device is concerned, 5 how the reservoir B is placed with respect to the storage-room A, or how the conduits D E are arranged with respect to said reservoir.

Having thus described my invention, I claim—

- 10 1. In a refrigerating apparatus, the combination, with a storage-room, of a deep tight contracted cold-air reservoir arranged above the ceiling of said room, a deep vessel for the refrigerant with tight or non-apertured walls 15 arranged in said reservoir, a conduit for cold dry air extending from near the bottom of said cold-air reservoir to the storage-room and opening into same at the ceiling, an air-conduit extending from the storage-room at its 20 ceiling to the upper part of said reservoir, and means, substantially as described, for controlling the flow of air through said conduits, as set forth.

- 25 2. A refrigerant-vessel for containing ice and salt, provided with a narrow downwardly-

directed passage, h, at its upper part for the brine to ooze or drip through over the exterior surface of said vessel, substantially as and for the purposes set forth.

3. An upright refrigerant-vessel, C, of elongated tubular form, made from sheet metal in two parts or sections, the lower section extending upward into the upper section telescopic ally, whereby a narrow downwardly-directed annular passage is formed between the two for 30 the brine to ooze or drip through and from, substantially as set forth.

4. The upright refrigerant-vessel C, provided with one or more downwardly directed narrow outlet-passages, h, close to its body, said 35 passage or passages being filled with fibrous material, h', to take up and deliver the brine, substantially as set forth.

In witness whereof I have hereunto signed my name in the presence of two subscribing 40 witnesses.

CHRISTIAN A. FREDERICKS.
